UNITED STATES PATENT OFFICE

158,893

COMBINED LAMP AND FLOWER PLANTER

Harry C. O'Brien, Los Angeles, Calif.

Application February 3, 1948, Serial No. 144,235

Term of patent 3½ years

(Cl. D48—25)

To all whom it may concern:

Be it known that I, Harry C. O'Brien, a citizen of the United States, residing at Los Angeles, in the county of Los Angeles and State of California, have invented a new, original, and ornamental Design for a Combined Lamp and Flower Planter, of which the following is a specification, reference being had to the accompanying drawing, forming part thereof.

Figure 1 is a perspective view of a combined lamp and flower planter, showing my new design;

Figure 2 is a side elevational view thereof, and Figure 3 is an end view of the same.

The essential features of the design reside in the portions shown by full lines.

I claim:

The ornamental design for a combined lamp and flower planter, as shown and described.

HARRY C. O'BRIEN.
